CARBURETOR.

Application filed November 20, 1922. Serial No. 602,032.

Our invention relates to carburetors for internal combustion engines, and particularly to the proportional-flow type of carburetor. More particularly, our invention 5 relates to that type of carburetor in which the air valve is suction-controlled. Other features of our improved carburetor relate to a two-movement fuel valve, this movement being in different dimensions; and 10 means whereby the movements of the fuel valve in one dimension are produced by and proportionate to the movements of the automatic air valve, the opening of the fuel valve during its movements in this dimension being, throughout the entire range of movement, 15 in an amount having a constant ratio to the opening of the air valve, the movement of the fuel valve in the other dimension being adapted continuously to change 20 the value of the constant ratio.

The means controlling the air supply are held closed, preferably spring-loaded, so as to permit the admission of air only above a certain predetermined minimum vacuum in 25 the casing immediately within the air opening, thereby obviating undesirable effects because of fluctuating fuel levels and because of the surface tension of the liquid fuel; also, obviating the change of the fuel 30 flow from the turbulent to the streamline flow. On the other hand, in order that the power of the engine may not be limited at full load, the restraint by which the air opening cover is held closed does not exceed 35 a certain predetermined maximum. Therefore, the vacuum chosen for the casing chamber into which the air and fuel both primarily feed lies between certain upper and lower limits.

40 The annexed drawings and the following description set forth in detail certain means embodying our invention, such means disclosing, however, but two of the various forms in which the principle of the invention may be applied.

In said annexed drawings:

Figure 1 represents a longitudinal section of one form of our improved carburetor, taken in the planes indicated by the line 45 I—I, Figure 2;

Figure 2 represents a longitudinal section, partially in plan, taken in the planes indicated by the line II—II, Figure 1;

Figure 3 represents a transverse section, taken in the planes indicated by the line 55 III—III, Figures 1 and 2;

Figure 4 represents a fragmentary longitudinal section, upon an enlarged scale, taken in the plane indicated by the line 60 IV—IV, Figure 3;

Figure 5 represents a perspective view, upon an enlarged scale, of the two-movement fuel valve;

Figure 6 represents a fragmentary longitudinal section of the lower end of the carburetor casing and showing a type of carburetor having a modified form of air inlet; 65

Figure 7 represents a longitudinal section 70 of a type of carburetor in which the two-movement fuel valve is operated in a somewhat different manner from that shown in Figures 1 to 6 inclusive, the structure being modified to show one way of effecting this manner of operation; 75

Figure 8 represents a fragmentary longitudinal section, taken in the plane indicated by the line VIII—VIII, Figure 7;

Figure 9 represents a transverse section, taken in the plane indicated by the line 80 IX—IX, Figure 7;

Figure 10 represents a fragmentary transverse section, taken in the plane indicated by the line X—X, Figure 7;

Figure 11 represents a fragmentary longitudinal section, upon an enlarged scale, taken in the plane indicated by the line 85 XI—XI, Figure 7;

Figures 12 and 13 represent, upon an enlarged scale, two parts forming the two-movement fuel valve of this type of carburetor; and 90

Figure 14 represents a bottom plan of said fuel valve parts when assembled, thus showing the resultant fuel port. 95

Referring to the annexed drawings in which the several elements are indicated in the different views by the same ordinals respectively, we indicate the main casing of our improved carburetor by the ordinal 1, 100 the same being provided with laterally-extended flanges 2 (Figures 1, 2 and 3) covered by a plate 3 to form an auxiliary chamber hereinafter fully described. A rectangular air inlet valve 4 and a rectangular throttle 105 valve 5, the latter being actuated from any

convenient point through the medium of a rod 5', are provided as indicated. The main casing is thus divided into several chambers indicated by the ordinals 7, 8 and 9, the same being hereinafter designated as chambers which are subject to atmospheric pressure, low vacuum, and high vacuum, respectively. The chamber formed by the auxiliary casing portions 2 and 3 is indicated by the ordinal 8' and is subject to the same low vacuum as the chamber 8, these two chambers being in free communication through the medium of the opening 6, as plainly indicated in Figure 1.

15 Rotatably mounted in one wall 2 of the auxiliary chamber 8' is a cylindrical, tubular member 10 communicating with a conduit 11 which in turn communicates with any suitable desired type of fuel float chamber not shown. As a matter of detail we have shown the connection between the cylinder 10 and the conduit 11 to consist in an enlarged chambered end 12 formed upon the latter and within which the outer open end 20 of the cylinder 10 is fitted, the two members 10 and 11 being retained in proper position by means of a plate 13 which is held by means of two screws 14 engaging into a wall 2 of the auxiliary chamber 8'. Within 25 the chamber 8' the cylinder 10 is formed with a rectangular opening 15 forming a fuel aperture adapted to register more or less, in a manner hereinafter fully described, with a corresponding fuel aperture 18 formed in an outer sleeve member 16 surrounding and mounted upon the tubular member 10, thus forming a fuel port adapted to discharge into a channel 19 (Figure 4) formed between an arcuate boss 1' upon the 30 casing 1 and the peripheral surface of the sleeve 16, this passage 19 communicating through the medium of a port 20 with the chamber 9 or the high vacuum side of the throttle valve 5. The sleeve 16 is mounted to be longitudinally movable on the cylinder 10 by means of an adjusting screw 25 threaded through a wall 2 of the chamber 8' and acting upon the sleeve 16 to move the same against the tension of a spring 17 which encircles the cylinder 10 and abuts at 35 one end on wall 2 of the chamber 8' and at the other end the opposite face of the sleeve 16, all as plainly shown in Figures 2 and 3. We indicate the fuel port formed by the 40 overlapping areas of the openings 15 and 18 by the ordinal 26, Figure 4, and we indicate the port edge of the opening 18 by the ordinal 31 and the port edge of the opening 15 by the ordinal 32, Figure 5.

45 Secured to the air valve 4 is an arm 21 and secured to the sleeve 16 is an arm 23, these two arms being connected by a rod 22. The air valve 4 is normally maintained in closed position through the medium of a 50 spring 24. Also, the cylindrical tubular

member 10 can be rotated through the medium of an arm 27 integrally secured thereto and positioned exteriorly of the chamber 8', Figure 3, this arm 27 being actuated by means not shown. We may now well mention that this arm 27 introduces means for especially actuating the fuel valve for the idling condition of the engine.

55 It is evident from the foregoing description that, the spring 24 being placed under suitable tension to provide the desired differential of pressure between the chambers 7 and 8, the movements of the air valve 4, induced by the movements of the throttle valve 5 and the speed of the motor, will maintain this differential within the required limits, and this vacuum of the chamber 8 produced by this differential will be termed the "low tension vacuum". By the phrase "low vacuum", as applied to chamber 8, we refer to a vacuum that is, preferably, kept to about one pound or less; whereas, in practice, the vacuum in chamber 9 may at times be as high as eight pounds; and, of course, the pressure in chamber 7 is atmospheric. Spring 24 attached to air valve 4 will maintain the vacuum in chamber 8 within sufficiently close limits to prevent any material change in the relative flow of air to the liquid fuel, due to variations of vacuum in said chamber 8. This low vacuum will also be maintained in the chamber 8'. During the manufacture of the carburetor a suitable tension would be determined for the spring 24, according to the character of the carburetor, the service for which the same is designed, and the stresses to which springs are subjected according to standard published works on springs. It is evident that the fuel port 26 discharges into this low vacuum maintained in the chamber 8'. Therefore, the air and the fuel will each discharge into a low vacuum and this vacuum will be the same. Now, further, the opening and closing of the fuel port 26, due to the mechanical assembling hereinbefore described and shown in the accompanying drawings, will be proportional to the opening and closing of the air valve 4. The aperture 30 through which the air enters the chamber 8 is rectangular, as plainly shown in Figure 3, and, as mentioned above, the openings 15 and 18 forming the fuel nozzle are rectangular so that any increment of air valve and fuel valve openings will admit a corresponding increment of air and fuel. The ratio between the openings of the air and fuel valves being once determined, this ratio remains constant throughout the whole range of operation of the air valve. In order that the turbulent flow of the fuel may be preserved throughout the entire range of operation, despite the fluctuations in vacuum encountered in practice, we load the air valve 4 by a spring 24 between certain lower 120

125 130

and upper limits of vacuum, preferably a lower limit of about 2 ounces and an upper limit of about 1 pound below atmosphere, i. e., between the inside of chamber 8 and the atmosphere. The reasons for these practical limits are: If the suction in chamber 8 is much more than one pound the power of the engine is limited at full load. If the suction is much less than 2 ounces, there is 10 an undesired effect from fluctuating fuel levels and from the surface tension of the liquid fuel; also, the fuel flow may change from the turbulent to the streamline flow, which causes variations in the fuel flow very 15 disproportionate to the variations in the air flow. Although, as above stated, practical operation presents certain fluctuations of the vacuum, still the tension of the spring 24 is determined for any one carburetor so as 20 to provide a fixed vacuum in the chamber 8 at some point between two ounces and one pound, as deemed desirable, and in theory this vacuum is considered to be maintained constant, although in practice it actually varies, this variation being well within the 25 above limits under usual operating conditions and not affecting the constant ratio between the effective areas of the fuel and air openings. In our improved type of carburetor, a considerable friction in the air and 30 fuel valve mechanism, or a wider fluctuation in the differential pressure between chamber 8 and the air intake 7, has no effect on the relative flow of air to fuel either in 35 theory or practice. The port 20 by means of which the fuel enters the chamber 9 is made just large enough to pass the fuel at the maximum opening of the throttle valve 5 without any restrictive or choking effect. This 40 determination of the size of the port 20 is obtained by experiments and tests of the type of carburetor for the particular service required. It will be noted that the length of the port 20 is equal only to the thickness of the wall of 45 the casing 1, so that the transfer of the fuel or mixture from the low vacuum chamber 8' to the high vacuum chamber 9 is through a conduit which both in length and cross-sectional area obviates the segregated feeding 50 of fuel and air globules and obviates any restrictive or choking effect, so that the uniformity of the mixture fed to the engine is not impaired by any conditions attaching to the by-pass 20.

55 It will be noted that the air and gas are mixed upon the high vacuum side of the throttle valve 5 and that, therefore, all of the fuel is by-passed from the low vacuum of the chamber 8' to the high vacuum of the 60 mixing chamber 9. The advantages of this particular operation reside in the facts that the proportioning of the fuel is easier to accomplish in the low vacuum chamber; whereas, the mixing of the fuel with the air in the 65 high vacuum chamber provides an unob- structed passage for the mixture into the engine manifold. Inasmuch as in carburetor practice it is desirable to atomize and vaporize the fuel to as great an extent as possible, this effect is partially nullified if the mixing 70 takes place on the low vacuum side of the throttle because the spray condenses on the throttle and feeds off in relatively large drops. Also, our mixing upon the high vacuum side of the throttle results in the 75 flow of a homogeneous mixture to the engine manifold; whereas, the feeding of the fuel off the throttle in relatively large drops, when the mixing has taken place on the atmospheric side of the throttle, results in a 80 more or less irregular mixture flowing to the engine manifold. Also, the atomization is best accomplished at the point of highest velocity. This point is on the high vacuum side and close to the throttle margin, and 85 our construction permits by-passing all the fuel to this point.

90 It will be evident that the operation thus far described relates only to the automatic operation occasioned by the suction-actuated air valve. Now, by means of the adjusting screw 25, the sleeve 16 can be moved longitudinally to provide different longitudinal openings for the fuel port 26. It is evident, therefore, that any desirable range 95 of fuel feed for motor operation, from idling to full throttle, may be chosen through the medium of the proper setting of the adjusting screw 25 and then, under the action of the throttle and the pull of the engine, the 100 fuel valve through the medium of the air valve will move through this chosen range of openings. Inasmuch as the fuel port 26 is rectangular, the area of said port 26 will vary in direct proportion as the distance 105 between the port edges 31 and 32 varies, illustrated by the distance A—B, Figure 5. Therefore, any adjustment effected by the screw 25 will be proportional for all automatic movements of the fuel valve and hence 110 for all openings of the throttle and all speeds of the motor. We have provided, then, two movements of the fuel valve, at an angle to each other, one movement feeding the fuel proportionately to the flow of air and the 115 other movement varying this proportion. It will be noted that the automatic control of the fuel and air valves maintains a constant ratio between the effective areas of the fuel 120 valve and air valve openings for all automatic movements; further, that the manual control of the fuel valve provides for changing this ratio of effective areas of the fuel valve and air valve openings from one constant ratio value to another constant ratio 125 value.

125 We form the carburetor wall 1 with an offset 35 at the point where the air valve 4 touches the wall 1 when said air valve is in closed position. The function of this off-

set 35 is to aid in making the air opening 30 proportional to each degree of angular opening of the valve 4, the opening of the fuel valve 18 being proportional to each degree of angular opening, thus insuring the constant ratio of fuel to air at all demands on the carburetor, the arms 21 and 23 being of the same length and parallel.

We also provide means for aiding in drawing the mixture through the port 20 and for atomizing and vaporizing the fuel. These means reside in an atomizing lug 28 secured to the casing wall adjacent the mixing-chamber-end of the port 20 and upon the air inlet side of the port 20. Furthermore, in the construction shown, for instance, Figure 4, this lug intersects the projection of the port 20 so that the mixture actually impinges upon the overhanging portion 28² of the lug 28 which has a marked nebulizing effect, thus aiding in obtaining the desired vaporization of the fuel. The main effects of the lug 28, whether or not the same overhangs the port 20, viz, the aiding in drawing the fuel through the port 20 and the atomizing and vaporizing of the fuel are occasioned as follows: First, as regards the drawing of the fuel through the port 20: When the throttle 5 is in its closed or nearly closed position, the vacuum in the mixing chamber 9 is relatively high and the fuel is drawn through the port 20 rapidly by said high vacuum, but as the throttle 5 is opened, the vacuum in the mixing chamber 9 drops until at full open throttle the vacuum in said chamber 9 is relatively low. However, the air at full throttle opening passes at high velocity over the lug 28 and produces a partial vacuum immediately forward of said lug or at the port 20, thus aiding in drawing the fuel through said port into the mixing chamber 9. Second, as regards the atomizing and vaporizing effect of the lug 28: When the throttle 5 is in its idling or nearly closed position, the high vacuum in the mixing chamber 9 draws the air at high velocity over the lug 28, and as the throttle 5 opens, the velocity of the air through the combined passage 7—8—9 of the carburetor casing increases, thus maintaining a high velocity of air over the lug 28 at all times. The air thus passing over the edge 28² of the lug 28 at high velocity has a very strong atomizing effect on the fuel entering through the port 20. As before mentioned, inasmuch as the mixing of the fuel and air takes place upon the high vacuum side of the throttle, this atomizing and vaporizing effect of the lug 28 upon the fuel is not later neutralized by the fuel condensing in drops upon the throttle.

In one slightly modified type of carburetor shown in Figure 6, we provide independent means for regulating the initial position of the fuel valve. These means con-

sist in the provision in the atmospheric chamber 7 of a pivoted platform 33 capable of adjustment through the medium of an adjusting screw 34, whereby it is apparent that the closed position of the air valve 4 can be regulated and hence through the members connecting the air valve and the fuel valve the closing or initial position of the latter can be regulated.

Referring to the type of carburetor shown in Figures 7 to 14 inclusive, the modifications over and above the type shown in Figures 1 to 6 consist largely in a structural arrangement whereby the automatic adjustment of the fuel valve, proportionate to the movements of the air valve, are due to a relatively longitudinal movement of registering openings, and the manual adjustment of said openings so as to set the fuel nozzle in any desired range of fuel feeds is accomplished by a relative rotary movement of said openings. Referring to the detail of this construction, the rod 22' which, through the medium of the movements of the suction-actuated air valve 4', controlling the air opening 30', longitudinally moves a cylindrical rod 16' relatively to a cylindrical tubular member 10' is pivoted intermediate its ends through the medium of a pin 38 upon a member 40 intersecting the wall 36 of the auxiliary chamber 37 and screwed into finger piece 41. Therefore through the medium of finger piece 41 and the action of the forked end 43 of the rod 22' upon member 44 secured to rod 16', the rod 16' can be moved longitudinally, thereby effecting the desired initial opening of the fuel port 26', or idling adjustment. The member 43 actually engages a collar 44² loosely mounted upon the rod 16'. The spring 24' encircles rod 16' and bears at one end against a floating washer 44² disposed adjacent said member 44 and at the other end against the wall 36 of said chamber 37, and is assembled in the carburetor under compression and is under compression at all times performing several functions, viz, to give a differential pressure between chambers 7 and 8 by tending to close valve 4'; to automatically take up all slack in moving joints in the linkage; also, to overcome any binding or sticking of the fuel-valve rod 16'. A lock nut 42 is provided adjacent the finger piece 41, as plainly shown in Figure 7. It is also evident that the pivotal point of the rod 22' upon the member 40 is disposed nearer the forked end 43 of said rod than it is to that end of the rod 22' which is secured to the arm 21'. Furthermore, as plainly indicated by the ordinals 22², we provide a further adjustment for the movements of the rod 16' by the provision of a plurality of points at which the arm 21' and the rod 22' may be secured together.

A cylindrical tubular member 10' is se-

cured to a casing member 1² which is fastened to the main casing 1 a spaced distance from the latter so as to form a passage 19' communicating with the chamber 8 through the medium of an opening 8² in the wall of the casing 1, the outer end of said cylindrical member 10' communicating with a fuel conduit 11' and the inner end of member 10' passing through opening 8², as plainly shown in the enlarged section in Figure 11. This opening 8² forms an auxiliary chamber having the same vacuum as the chamber 8 which latter vacuum is maintained within the required limits by the movements of the suction-actuated air valve 4'. The tubular member 10' is formed at one end with an open-ended rectangular opening 15' and is adapted to receive at this end the adjacent end of the cylindrical member 16', substantially one-half of the latter being cut away to form an opening 18' adapted to register more or less with the opening 15', to form a fuel port 26', as plainly shown in Figure 14, according to the longitudinal position of the cylindrical member 16'. As before explained, this longitudinal position of the cylindrical member 16' is automatically determined by the movements of the suction-actuated air valve 4'. It is evident that, if means be provided for relatively rotatably moving the members 10' and 16', different ranges of fuel feed may be provided, each of which ranges will be covered by the automatic longitudinal movement of the cylindrical member 16' and its fuel opening portion 18'. This relative rotatable movement is effected by means for manually adjusting the rotative position of the cylindrical member 16'. These means consist in the member 44 which is clamped to the member 16' and which is provided with an extended tongue 44' to which is secured a pin 46 adapted to engage a slot 48 formed in a follower 47 engaging a screw 49 rotatably mounted in the walls 36 of the auxiliary casing 37 and provided with a finger piece 50, as plainly shown in Figures 8 and 10. Inasmuch as the pin 49 is longitudinally fixed, it is evident that a turning movement of the finger piece 50 will cause the follower 47 to travel longitudinally upon the pin 49 thereby turning the clamp 44 through the medium of the pin 46 and thus thereby turning the cylindrical member 16', to which the clamp 44 is secured, and thus relatively rotatably adjusting the position of the openings 15' and 18' forming the fuel port 26'. A'—B', Fig. 14, denotes the adjustable distance between the port edges 31' and 32'. A guide and support for the free end of the follower 47 is provided through the medium of a pin 52 mounted in the casing 36 and which intersects a slot 51 formed in said follower 47, as plainly shown in Figures 7 and 10. In this type of car-

buretor the fuel discharges from the port 26' into the chamber 8² which is maintained at the same vacuum as the chamber 8 and thence the fuel by-passes the throttle 5, through the medium of the channel 19' and port 20', to the mixing chamber 9.

We do not propose that one of the movements of our two-movement fuel valve should necessarily be manually controlled, since an automatic actuation would be within the principle of our invention. Furthermore, this particular movement could be automatically controlled by a thermostat to compensate for temperature variations which require a variation of the ratio of area of the fuel port to the area of the air valve opening in order to keep the proportion of fuel and air constant. It is well known that the viscosities of liquid fuels vary with the temperature and that the rate of flow of the fuel through a given orifice varies with the viscosity, hence, it is essential to compensate for the temperature variation if the ratio of fuel to air is to be kept constant. In aeronautic practice, the movement which we have shown and described as manually controlled could be operated by an aneroid bellows to compensate for the variation in richness of mixture resulting from varying altitudes.

Our construction of carburetor also acts as an automatic fire-trap. The air valve 4 would automatically close due to the back pressure of the air, and the fire would be trapped by this closing of the air valve. Inasmuch as fire requires at least 1/32-inch opening to pass, and we have no opening in our carburetor more than 1/64-inch, the fire would be effectively trapped.

We have illustrated the carburetor in the accompanying drawings for use in horizontal position. In this position, as plainly shown in Figure 4, the channel 19 serves to aid in feeding the fuel by conducting the same by gravity to the port 20, after it has been proportioned through the fuel port 26.

What we claim is:

1. In carburetors, the combination of a casing having an air inlet, a fuel port, and a mixture outlet; a throttle valve mounted in said casing and dividing said casing into an air chamber and a mixing chamber; a suction-actuated valve controlling said air inlet; a two-movement valve controlling said fuel port, said fuel valve being connected to said air valve and moved automatically in one direction by the movements of said air valve so as to vary the area of the fuel valve opening, throughout the entire range of movement, in an amount having a constant ratio to the area of the opening of the air valve, said fuel valve being movable in the other direction to change the constant ratio from one value to another;

and means providing for the admission of fuel under the same amount of vacuum as that under which the air is admitted.

2. In carburetors, the combination of a casing having an air inlet, a fuel port, and a mixture outlet; a throttle valve mounted in said casing and dividing said casing into an air chamber and a mixing chamber; a suction-actuated air valve, said air valve being loaded to maintain a vacuum within vacuum limits which preserve the turbulent flow of the fuel; a two-movement valve controlling said fuel port, said fuel valve being connected to said air valve and moved automatically in one direction by the movement of said air valve so as to vary the area of the fuel valve opening, throughout the entire range of movement, in an amount having a constant ratio to the area of the opening of the air valve, said fuel valve being movable in the other direction to change the constant ratio from one value to another; and means providing for the admission of fuel under the same amount of vacuum as that under which the air is admitted.

3. In carburetors, the combination of a casing having an air inlet, a fuel port, and a mixture outlet; a throttle valve mounted in said casing and dividing said casing into an air chamber and a mixing chamber; a suction-actuated air valve, said air valve being loaded so as to maintain a vacuum substantially between two ounces and one pound; a two-movement valve controlling said fuel port, said fuel valve being connected to said air valve and moved automatically in one direction by the movements of said air valve so as to vary the area of the fuel valve opening, throughout the entire range of movement, in an amount having a constant ratio to the area of the opening of the air valve, said fuel valve being movable in the other direction to change the constant ratio from one value to another; and means providing for the admission of fuel under the same amount of vacuum as that under which the air is admitted.

4. In carburetors, the combination of a casing having an air inlet, a fuel port, and a mixture outlet; a throttle valve mounted in said casing and dividing said casing into an air chamber and a high vacuum chamber, the latter chamber serving as a mixing chamber closely adjacent the throttle valve edge when the latter is in its closed position; a suction-actuated air valve, said air valve being loaded so as to maintain a vacuum between certain predetermined upper and lower vacuum limits; means forming an auxiliary chamber subject to the same vacuum as the air chamber; means admitting air to said auxiliary chamber; a two-movement fuel valve communicating with said auxiliary chamber and controlling said fuel port, said fuel valve

being connected to said air valve and moved automatically in one direction by the action of said air valve so as to vary the area of the fuel valve opening, throughout the entire range of movement, in an amount having a constant ratio to the variation in area of the air opening, said fuel valve being movable in the other direction to change the constant ratio from one value to another; and means forming a passage communicating with said auxiliary chamber and said mixing chamber.

5. In carburetors, the combination of a casing having an air inlet, a fuel port, and a mixture outlet; a throttle valve mounted in said casing and dividing said casing into an air chamber and a mixing chamber; a suction-actuated valve controlling said air inlet; a two-movement valve having a fuel port adapted to register with said first-mentioned fuel port, the opposite limiting edges of the inlet opening formed by said fuel ports being parallel, said fuel valve being connected to said air valve and moved automatically in one direction by the movements of said air valve, whereby the area of the fuel valve opening varies in an amount having a constant ratio to the variation in area of the air valve opening, said fuel valve being movable in the other direction to change the constant ratio from one value to another; and means providing for the admission of fuel and air under the same amount of vacuum.

6. In carburetors, the combination of a casing having an air inlet and a fuel port both of rectangular cross-section, said casing also having a mixture outlet; a throttle valve mounted in said casing and dividing said casing into an air chamber and a mixing chamber; a suction-actuated valve controlling said air inlet, said air valve maintaining a vacuum between predetermined minimum and maximum vacuum limits; a two-movement valve having a fuel port of rectangular cross-section adapted to register with said first-mentioned fuel port and having an opening edge at right angles to the sides of said first-mentioned fuel port, said fuel valve being connected to said air valve and moved automatically in one direction by the movements of said air valve, whereby the area of the fuel valve opening will be varied in an amount having a constant ratio to the variations in area of the air valve opening, said fuel valve being movable in the other direction to change the constant ratio from one value to another; and means providing for the admission of fuel under the same amount of vacuum as that under which the air is admitted.

7. In a carburetor having a mixing passage and a throttle in said passage, means for discharging an initial mixture of fuel and air through the wall of said passage ad-

- 5 jacent the edge of said throttle when the latter is in its closed position, means for passing fuel through the wall of said passage in all positions of the throttle, and
 10 means attached to the wall of said mixing passage adjacent said discharging means to receive the impact of the discharged mixture and facilitate the atomization of the liquid content.
- 10 8. In carburetors, the combination of a casing providing a motor intake and providing for the admission of air; a throttle valve mounted in said casing, the air being admitted on the low vacuum side of said throttle valve; a suction-actuated valve controlling the admission of air; means permitting a main air stream to pass by the throttle valve; means permitting an auxiliary air stream to by-pass the throttle valve; a conduit adapted to communicate with a source of fuel supply; a rotatable sleeve enclosing said conduit, said conduit and sleeve being formed with openings adapted increasingly to register upon the rotation of said sleeve; means for adjusting said sleeve longitudinally; means providing communication between said sleeve opening and the interior of said casing upon the high vacuum side of the throttle valve; means permitting the mixing 20 of said auxiliary air with the fuel as the latter passes to the high vacuum side; means connecting said suction-actuated valve and said sleeve to move the same proportionately; and a spring tending to hold said suction-actuated valve closed.
- 15 9. In carburetors, the combination of a casing having an air inlet and a mixture outlet; a throttle valve mounted in said casing and dividing said casing into an air chamber and a high vacuum chamber; a fuel port and a valve therefor; a valve for said air inlet; means for operating said air and fuel valves; means forming a low vacuum chamber into which said air and fuel valves provide entrance, the high vacuum chamber into which the air passes by the throttle valve forming a mixing chamber; means forming a passage communicating with said low vacuum chamber and said mixing chamber and permitting a mixture of fuel and air under the pull of the high vacuum to by-pass the throttle valve to said mixing chamber; and a vaporizing lug disposed on the air intake side of the mixing-chamber-end of said fuel 30 passage, said lug also increasingly aiding the high vacuum pull upon the fuel as the throttle valve opens.
- 20 10. In carburetors, the combination of a casing provided with a throttle valve, said casing having a rectangular opening to the atmosphere; a suction-actuated valve controlling said opening; a member adapted to communicate with a source of fuel and having a rectangular wall opening; a second member communicating with the interior of said casing and having a rectangular opening adapted to register with said wall opening; means connecting said suction-actuated valve and one of said members to move the same proportionately; and means for relatively moving said members so as to vary the registering areas of their openings in a relation angular to that produced by said proportionate movements.
- 25 11. In carburetors, the combination of a casing having a chamber of rectangular cross-section and formed at one end with a motor intake and at the other end with an air-opening; a spring-loaded suction-actuated valve for said opening; a throttle valve; a port formed in the casing in the rear of said throttle valve; an auxiliary casing forming a chamber communicating with the main casing through said port and also communicating with the main chamber adjacently behind said air valve; means forming a conduit adapted to communicate with a source of fuel supply and having a rectangular fuel port and a movable valve controlling said fuel port and having an opening edge at right angles to the sides of said port, said last-named valve permitting fuel discharge into said auxiliary chamber adjacently to said casing port; means connecting said air valve and said fuel valve to move the latter proportionately to the movements of the former; and means for adjusting said fuel valve relative to the port which it controls in a direction angular to that in which it is moved by said connecting means.
- 30 12. In carburetors, the combination of a casing formed at one end with a motor intake and at the other end with an air-opening; a spring-loaded suction-actuated valve for said opening; a throttle valve; a port formed in the casing in the rear of said throttle valve; a lug secured longitudinally of the casing and having its rearward end positioned adjacent the inner end of said port and formed with a bottom rearward extension intersecting the projected axis of said port; an auxiliary casing forming a chamber communicating with the main casing through said port and also communicating with the main chamber adjacently to behind said air valve; means forming a conduit adapted to communicate with a source of fuel supply and having a movable valve, said last-named valve permitting fuel discharge into said auxiliary chamber adjacently to said port; and means connecting said air valve and said fuel valve to move the latter proportionately to the movements of the former.
- 35 13. In carburetors, the combination of a casing formed at one end with a motor connection and at the other end with an air opening; a spring-loaded suction-actuated valve for said opening; a throttle valve; a port formed in the casing in the rear of said

- throttle valve; a concave boss formed exteriorly of the casing, said port intersecting said boss; an auxiliary casing forming a chamber communicating with the main casing through the said port and also communicating with the main casing adjacently behind said air valve; means forming a conduit adapted to communicate with a source of fuel supply and having a fuel port and a movable valve controlling said fuel port, said last-named valve permitting fuel discharge into said auxiliary chamber within said boss and adjacent said casing port; means connecting said air valve and said fuel valve to move the latter proportionately to the movements of the former; and means for regulating said proportion.
14. In carburetors, the combination of a casing formed at one end with a motor intake and at the other end with an air opening; a spring-loaded suction-actuated valve for said opening; a throttle valve; a port formed in the casing in the rear of said throttle valve; a concave boss formed exteriorly of said casing, said port intersecting said boss; an auxiliary casing forming a chamber communicating with the main casing through said port and also communicating with the main casing adjacently behind said air valve; means forming a conduit adapted to communicate with a source of fuel supply and having a fuel port and a movable valve, controlling said fuel port, said last-named valve permitting fuel discharge into said auxiliary chamber within said boss and adjacent said casing port; means connecting said air valve and said fuel valve to move the latter proportionately to the movements of the former; means for regulating said proportion; and an atomizing and suction lug forward within said main casing adjacently rearwardly of the inner end of said casing port.
- Signed by us this 28 day of October, 1922.

CLAYTON E. MONOSMITH.
DAVID J. MONOSMITH.
OLNEY B. MONOSMITH.

CERTIFICATE OF CORRECTION.

Patent No. 1,666,296.

Granted April 17, 1928, to

CLAYTON E. MONOSMITH ET AL.

It is hereby certified that error appears in the printed specification of the above numbered patent requiring correction as follows: Page 5, line 72, strike out the paragraph commencing with the word "We" and all to and including the word "altitudes" in line 95; and that the said Letters Patent should be read with this correction therein that the same may conform to the record of the case in the Patent Office.

Signed and sealed this 19th day of June, A. D. 1928.

(Seal)

M. J. Moore,
Acting Commissioner of Patents.

- throttle valve; a concave boss formed exteriorly of the casing, said port intersecting said boss; an auxiliary casing forming a chamber communicating with the main casing through the said port and also communicating with the main casing adjacently behind said air valve; means forming a conduit adapted to communicate with a source of fuel supply and having a fuel port and a movable valve controlling said fuel port, said last-named valve permitting fuel discharge into said auxiliary chamber within said boss and adjacent said casing port; means connecting said air valve and said fuel valve to move the latter proportionately to the movements of the former; and means for regulating said proportion.
14. In carburetors, the combination of a casing formed at one end with a motor intake and at the other end with an air opening; a spring-loaded suction-actuated valve for said opening; a throttle valve; a port formed in the casing in the rear of said throttle valve; a concave boss formed exteriorly of said casing, said port intersecting said boss; an auxiliary casing forming a chamber communicating with the main casing through said port and also communicating with the main casing adjacently behind said air valve; means forming a conduit adapted to communicate with a source of fuel supply and having a fuel port and a movable valve, controlling said fuel port, said last-named valve permitting fuel discharge into said auxiliary chamber within said boss and adjacent said casing port; means connecting said air valve and said fuel valve to move the latter proportionately to the movements of the former; means for regulating said proportion; and an atomizing and suction lug forward within said main casing adjacently rearwardly of the inner end of said casing port.
